(57) CLAIM

I claim the ornamental design for a handlamp, as shown and described.

DESCRIPTION

FIG. 1 is a front view of a handlamp;
FIG. 2 is a rear view of the handlamp of FIG. 1;
FIG. 3 is a left-side view of the handlamp of FIG. 1;
FIG. 4 is a right-side view of the handlamp of FIG. 1;
FIG. 5 is a top view of the handlamp of FIG. 1;
FIG. 6 is a bottom view of the handlamp of FIG. 1; and
FIG. 7 is a perspective view of the handlamp of FIG. 1.
The broken line showing represents unclaimed portions of the article and forms no part of the claimed design.

1 Claim, 7 Drawing Sheets
